CLAIM

The ornamental design for a display screen or portion thereof with an icon image, as shown and described.

DESCRIPTION

The present application is related to U.S. Design patent application Ser. No. 29/674,456, entitled Display Screen or Portion Thereof with an Icon Image, filed concurrently herewith, the entire disclosure of which is incorporated herein by reference.

The patent or application file contains at least one drawing executed in color. Copies of this patent or parent application publication with color drawing(s) will be provided by the Office upon request and payment of the necessary fee.

FIG. 1 is a front view of a first image in a sequence of a display screen or portion thereof with an icon image;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof; and,

FIG. 11 is a front view of an eleventh image thereof.

The dash-dot broken lines showing portions of the graphical user interface and display screen are included for the purpose of illustrating portions of the article and form no part of the claimed design. In the figures, the perimeters of the portion of the underlying display screen and the graphical user interface are understood to be flush.

The appearance of the transitional image sequentially transitions between the images shown in FIGS. 1-11. In another embodiment, the transitional image sequentially transitions between the images shown in FIGS. 1, 3 and 5. In another
